UNITED STATES PATENT OFFICE.

JOSEPH FLEET, OF HARRISBURG, PENNSYLVANIA, ASSIGNOR TO UNITED SHOE MACHINERY COMPANY, OF PATERSON, NEW JERSEY, A CORPORATION OF NEW JERSEY.

WORK-SUPPORT.

1,198,430.

Specification of Letters Patent. Patented Sept. 19, 1916.

Application filed October 2, 1912. Serial No. 723,504.

To all whom it may concern:

Be it known that I, JOSEPH FLEET, a citizen of the United States, residing at Harrisburg, in the county of Dauphin and State 5 of Pennsylvania, have invented certain Improvements in Work-Supports, of which the following description, in connection with the accompanying drawings, is a specification, like reference characters on the drawings indicating like parts in the several 10 figures.

This invention relates to shoe machines, and particularly to a work support which may be found of especial use in connection 15 with bed lasting machines.

In lasting shoes upon machines of the bed type, such, for example, as that shown in United States Letters Patent to Brock, No. 1,018,477, the toe portion of a shoe rests 20 upon a pad against which it is held more or less securely by the jacking mechanism and preferably also by a hold-down, and the wipers are closed in against the side of the toe portion and are moved upwardly to 25 bring the upper into close contact with the last, to remove wrinkles therefrom, and after applying substantial tension thereto to wipe the upper over the feather of the insole and hold it in place during the application 30 of the toe wire. In performing this operation, however, some difficulty has been experienced, especially when making shoes on lasts having high toes, because of the tendency of the upper to bridge across the 35 low part of the last between the toe and the instep. Another difficulty consists in distortion or "bowing" of the tip line due to the tension applied to the toe of the upper while insufficient pressure was applied over 40 the tip line to hold the upper firmly against the wood of the last.

It is accordingly an object of the present invention to provide, in connection with means for supporting the toe, means for preventing 45 the bridging of the upper by holding the upper against the wood of the last and also for keeping the tip line straight by pressure exerted along the tip line.

An important feature of the invention 50 consists in means for applying pressure locally to the box of the toe, preferably along the line, or lines, where the box is sewed to the upper, commonly known as the tip seam. This localized pressure is preferably applied 55 resiliently through a rather stiff spring, and

preferably means is provided for equalizing the pressure upon the different portions of the tip seam to which pressure is applied.

It is also a feature of the invention that the means for applying pressure locally to 60 the tip seam is combined with means which may be relatively movable and of usual construction for supporting the toe of the shoe. As embodied herein a toe rest of usual construction is provided and in the rear of the 65 toe rest is located an additional narrow pad which is adapted to engage the shoe along the tip seam and is so mounted in its support that it may tip about an axis extending longitudinally of the shoe and substantially 70 in the plane of the sole to accommodate itself to variations in the relative thickness of the two sides of the last. The pad carrying member may be supported on suitable plungers, as shown, and may be forced upwardly to engage the shoe by a suitable spring.

These and other features of the invention, including novel arrangements and combinations of parts, will appear more fully from 80 the following detailed description, when read with reference to the accompanying drawings and from the appended claims.

Figure 1 is a perspective view of a toe rest embodying the invention; and Fig. 2 85 is a side elevation partly in longitudinal section of a machine provided with a toe rest embodying the present invention.

In the drawings, Fig. 2, the reference character A indicates the toe head of a lasting machine upon which the mechanism for carrying and operating the wipers B is located. The toe head A is provided with a rearward projection 2 having a vertical hole 90 in which the toe post 4 is mounted for longitudinal movement, a screw 6 being arranged to enter a groove in the post 4 to prevent rotation of the post. Upon the upper end of the post 4 is a block 8 on which the toe pad 10 is mounted by a block 12 having the usual transverse slide 14 and longitudinal slide 16. At the rear of the pad 10 is mounted a rocking clamp comprising a pad 20 and a box 22. The pad is 95 preferably of rubber, and of such extent longitudinally as to engage the shoe locally in the region of the tip seam. The pad 20 is preferably crescent-shaped and is mounted in the box 22 which is segment-shaped and is seated in a segment-shaped cavity in 100 110

a block 24, the latter being mounted for vertical movement on plungers 26 which extend through the sleeves 28 rigidly mounted in the block 8. Between the plungers 28 is 5 a third plunger 30 which passes freely through a hole in the block 8 and upon which is a spring 32 acting to elevate the pad 20. Limiting stops are provided by pins 33 passing through the lower ends of the 10 plungers 26 and engaging the lower face of the block 8. To retain the pad 20 and box 22 in position in the block 24 a pin 34 is provided which passes through the pad 20 and box 22 and rests in slots 36 formed in 15 the sides of the block 24 and curved from the center of movement of the box 22.

In operation the shoe is jacked in the usual way, the post 4 being raised to press the pads 10 and 20 with considerable force 20 against the shoe which is held in position, not only by the usual heel lasting mechanism but preferably also by a hold-down C. During this jacking operation the pad 20, being normally located above the pad 10 (as 25 shown in Fig. 1) engages the shoe first and presses the upper at the tip seam firmly against the last before the pad 10 engages the shoe, and aids the pad 20 in holding the upper in position. The pressure of the pad 30 20 locally at the tip line continues during the lasting operation and prevents the central portion of the tip seam from being drawn forward by the tension applied to the upper in the lasting operation resulting in 35 a bowed tip seam which is unsightly and otherwise objectionable.

Having described my invention, what I claim as new and desire to secure by Letters Patent of the United States is:—

40 1. A work support comprising a vertically rigid toe rest, a yielding presser located at the rear of the rest, normally projecting above said rest and adapted to contact with the shoe along the tip seam, and 45 means for equalizing the pressure applied by said yielding presser to the tip seam.

50 2. A work support comprising a crescent-shaped member which is mounted for lateral rocking movement, is restrained from horizontal movement and is adapted to contact with the toe locally along the tip seam to clamp the upper of the shoe against the last and to prevent movement of the upper longitudinally of the last during the lasting 55 of the toe.

60 3. A work rest comprising a rigid support for the toe of a shoe and laterally rocking supplemental means for conforming to the surface of the last and applying equalized pressure to clamp the upper to the last along the tip seam.

65 4. A work support comprising a pad for sustaining the toe portion of the shoe and means movable about an axis extending longitudinally of the last arranged to act upon

the shoe prior to its contact with the pad to force the upper against the last and prevent bridging of the upper between the instep and toe when operating upon shoes with high toes.

70 5. A work support comprising a pad for sustaining the toe portion of the shoe, and means arranged to contact with the shoe prior to its contact with the pad and to exert a pressure along the horizontally disposed portion of the tip seam to force the upper closely against the last along its thinnest portion, said means being mounted for movement about an axis extending lengthwise of the last and lying substantially in 80 the plane of the sole.

75 6. A work support comprising vertically rigid means for sustaining the shoe, a clamp mounted for rocking movement and arranged to clamp the upper against the last 85 at the tip seam, and means independent of the rocking movement for yieldingly supporting the clamp.

80 7. A work support comprising a toe rest and a tip seam clamp located toward the 90 heel of the shoe from the rest, resilient means for upholding the clamp, and a structure in addition to said means whereby the clamp is mounted to rock transversely of the shoe to adapt its position to the shape 95 and position of the last at the tip seam.

85 8. A work support comprising a two-part toe rest, one part being vertically rigid but constructed to permit movement thereof by the shoe in a plane parallel to the last bottom and the other part being restrained from movement in said plane and mounted to slide vertically.

90 9. The combination with a base 8 and a toe pad 10, of a pad 20, a plunger 30 passing through the base and secured to the pad 20, a spring 32 on the plunger and adapted to sustain the pad 20, guides 26 and stops 33 on the ends of the guides 26 for limiting 105 the movement of the plunger 30.

100 10. A work support, having in combination, a toe rest 10 having horizontal slides 12, 16 at right angles to each other, and a tip line rest 20 resiliently mounted on a spring 32 and having guides 26 to permit 115 movement of the tip line rest in a vertical direction only.

11. In a lasting machine, a toe rest comprising a vertically movable stem having a head, a toe support unyieldingly mounted 120 on the head, a tip seam clamp mounted on the head in the rear of the toe support to have a bodily yielding movement downwardly and means normally holding said clamp at a higher elevation than the toe 125 support.

12. In a lasting machine, a toe rest comprising a vertically movable stem having a head, a toe support unyieldingly mounted on the head and a clamp also mounted on 130

the head in the rear of the toe support and vertically movable therewith, and a spring between the head and the clamp which 5 yieldingly upholds the clamp in position to engage with the shoe and press the vamp into the depression between the high toe and the instep of a last prior to the engagement of the toe with the toe support.

13. A work support comprising a toe rest 10 and a crescent-shaped member which is mounted for lateral rocking movement, is restrained from horizontal movement and is adapted to contact with the toe locally

along the tip seam to clamp the upper of the shoe against the last and coöperate with 15 the toe rest in preventing movement of the upper longitudinally of the last during the lasting of the toe.

In testimony whereof I have signed my name to this specification in the presence 20 of two subscribing witnesses.

JOSEPH FLEET.
